US0D1104115S

(12) **United States Design Patent** (10) **Patent No.:** **US D1,104,115 S**
(45) **Date of Patent:** **** Dec. 2, 2025**

(54) **CAMERA LENS**

(71) Applicant: **GoPro, Inc.**, San Mateo, CA (US)

(72) Inventors: **John George Muhlenkamp, IV**,
Mapleton, UT (US); **Ian Copeland**
Griggs, San Francisco, CA (US)

(73) Assignee: **GoPro, Inc.**, San Mateo, CA (US)

(**) Term: **15 Years**

(21) Appl. No.: **29/949,371**

(22) Filed: **Jun. 26, 2024**

(51) **LOC (15) Cl.** **16-05**

(52) **U.S. Cl.**
USPC **D16/219**

(58) **Field of Classification Search**

USPC D16/134, 200, 219, 237
CPC . G03B 2217/243; G03B 17/565; G03B 17/56
See application file for complete search history.

(57) **CLAIM**

The ornamental design for a camera lens as shown and described.

DESCRIPTION

FIG. 1 is a front, upper, right perspective view of a camera lens of our new design;

FIG. 2 is a rear, lower, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a cross-sectional view thereof along line 9-9 of FIG. 7.

Broken lines of equal length (e.g., dash-dash) represent unclaimed portions of the camera housing and form no part of the claimed design.

1 Claim, 8 Drawing Sheets
